FILE DRAWER FACE PANEL

Florence S. Knoll, New York, N.Y., assignor to Knoll
Associates, Inc., New York, N.Y., a corporation of
New York

Filed Feb. 18, 1960, Ser. No. 59,437

Term of patent 14 years

(Cl. D33—19)

Fig. 1.

Fig. 2.

Fig. 3.

FIG. 1 is a front elevational view of a file drawer face panel, showing my new design;

FIG. 2 is a fragmentary cross-sectional view taken on the line 2—2 of FIG. 1, on an enlarged scale, showing the drawer pull design;

FIG. 3 is a fragmentary cross-sectional view taken on the line 3—3 of FIG. 1, showing the design of the label support.

The relative thickness of the face panel is shown by FIGS. 2 and 3 and the top or upper edge is plain.

I claim:

The ornamental design for a file drawer face panel, as shown and described.
